DETACHABLE, ADJUSTABLE SHAPE MOP HEAD

Elbert D. Smyth, Newark, Ohio

Application December 17, 1952, Serial No. 326,440

1 Claim. (Cl. 15—229)

This invention relates to dust mops, having specific reference to an improved yarn-containing fabric head of the type which is adapted for detachable application to various sizes and shapes of handle-mounted mop-supporting frames.

There are many types of dust mops now being produced by different manufacturers and available to the purchasing public. Each manufacturer of such mops, however, employs a head frame or block which is different in shape, physical dimensions, materials, and other respects from the frame or block of other manufacturers. These physical differences in the construction of such frame or block have required heretofore the employment of mop heads especially formed for or adapted to be received upon each particular make of head frame, with the result that merchants handling such mop heads as replacement items are required to carry in stock, or to obtain on special orders, a mop head peculiarly suitable to each make of mop.

It is, therefore, a primary object of the present invention to provide a replacement head for floor mops which is so constructed that it is entirely adaptable for application to a relatively wide variety of differently styled or shaped mop blocks or frames, whereby to enable the single replacement head of the present invention to be employed usefully and practically on a considerable number of differently formed frames which heretofore have required specially formed heads for use thereon.

Another object of the invention is to provide a fabric yarn-containing mop head adapted for ready attachment to an associated block member or frame of a mop, and wherein the formation and manner of attachment of the head to the block or frame of the mop are such as to maintain the head when in use thereon in a flat taut condition, avoiding undesired wrinkling or bunching thereof even when the shapes or forms of different block or frame members vary substantially.

Another object is to provide a yarn mop head adapted for taut and unwrinkled application to a frame or block of a dust mop, said head comprising a woven fabric sheet of canvas, twill, duck, or the like which carries on one side thereof a multiplicity of strands of relatively soft textile yarn, with the strands of yarn being disposed in relatively closely spaced relation to the marginal edge of the sheet, and wherein the outer edges of the fabric sheet are provided with stitching defining a continuous pocket or channel for the reception of one or more associated drawstrings, the body of the string being disposed within the confines of the continuous stitch-formed pocket, so that when the free ends of the string which project laterally through the stitching are drawn together, the binding forces exerted by the string on the head sheet stitching will be applied uniformly around the stitched edges of the head, adapting the latter quickly and snugly to the physical peculiarities of the frame on which the head is applied and in a manner precluding undesired wrinkling or bunching thereof.

Another object is to provide a mop head of this char-

2

acter wherein strains occasioned by tensioning the drawstring are removed from the stitching forming the drawstring pocket and are absorbed by reinforcing tapes applied over such stitching where the free ends of the drawstring pass laterally outwardly of such stitching, whereby to prevent the possible tearing or destruction of the pocket-forming stitching.

For a further understanding of the invention, reference is to be had to the following description and the accompanying drawing, wherein:

Fig. 1 is a top plan view of a mop provided with the mop head of the present invention;

Fig. 2 is an enlarged fragmentary top plan view of one end of the mop head;

Fig. 3 is a transverse vertical sectional view taken through the mop head on the plane indicated by the line 3—3 of Fig. 2;

Fig. 4 is a view similar to Fig. 2, but disclosing the underside of the mop head when the same occupies a flat position removed from an associated mop frame and, also, with the mop yarn removed therefrom;

Fig. 5 is a top plan view of the present mop head applied to a generally triangularly shaped frame;

Fig. 6 is a detailed fragmentary top plan view of the mop head in the region of one of the fabric reinforcing tapes, showing the reinforcing tape in partial horizontal section;

Fig. 7 is a detailed vertical sectional view taken along the line 7—7 of Fig. 6 and showing the relation of the fabric reinforcing tape to the drawstring and pocket-forming stitching; and

Fig. 8 is a fragmentary longitudinal vertical sectional view taken through one side of the present mop head as the same is mounted upon an associated mop frame.

Referring more particularly to the drawing, the numeral 1 designates the frame of a dusting or polishing mop. As previously stated, such frames vary widely in their size, shape, and general construction, each mop manufacturer usually producing a distinctive style. In this instance, the frame 1 has been shown as comprising a generally oval or elliptical wire body 2, although the same may be in the form or shape of a triangle, as shown in Fig. 5, or composed of a wooden, generally rectangular block, as shown in Fig. 8. In the form shown in Figs. 1—5, the wire frame is united intermediately of its length by transverse straps 3 formed with upstanding ears 4. Between these ears there is positioned the lower pivoting end 5 of a handle member 6, a pivot bolt 7 passing through apertures provided in the ears 4 and the end 5 in adjustably uniting the frame of the mop with the handle member.

Adapted for removable application to such a head frame is the yarn-carrying fabric head 8 of the present invention. The head, as shown, is formed to include a sheet 8a of fabric, such as canvas, twill, duck, or the like, having a multiplicity of strands of twisted yarn, indicated at 9, extending outwardly from one side thereof. The body of yarn substantially covers one side of the sheet 8a, but terminates in relatively closely spaced relation to the marginal edges 8b of the sheet, as shown in Fig. 3.

In order to secure the head to the mop frame in an interchangeable, secure, and taut manner, the sheet 8a is sewn marginally to provide the loop stitching, indicated at 10, producing a continuous pocket along the margin 8b. In this instance, there is received within the pocket of the stitching the intermediate portions of a pair of drawstrings 11. While a pair of such strings has been shown, it will be understood that a single string may be used if desired. A pair of such strings, however, provides greater facility in applying and removing the head from the mop frame and rendering it applicable to a wide variety of frame shapes.

In the use of the head, the latter is positioned around the frame of a mop in the usual manner. The free ends 12 of the drawstrings are grasped by an operator and drawn together in a manner stretching or tightening the cloth around the wire body of the head frame.

As shown particularly in Figs. 6 and 7, the fabric head 8 may be provided with reinforcing tapes 15 which are looped over the marginal edges of the sheet 8a where the free end portions of the drawstrings are directed laterally outwardly from the stitching 10 and stitched, as at 16, to the sheet in a manner producing strain-bearing loops through which the drawstrings 12 project. These reinforcing tapes receive stresses and strains incident to the tying of the drawstrings in a position holding the head to the mop frame and relieve the selvage stitching 10 of such strains. If desired, the drawstrings may be fastened to the sheet 8a by bar tacking or suitable adhesive, as at 17, intermediately of their lengths so that the strings will not become accidentally withdrawn from the stitching 10.

As stated, in lieu of using a relatively light wire frame, as indicated at 2, it will be understood that the frame or head holder may be of any suitable construction. In Fig. 8, for instance, the frame, shown at 13, may be of wood, metal, or other solid substances, whereby to develop weight to facilitate its use in floor wiping, mopping, scrubbing, or polishing operations. My improved mop head, because of its adjustability as above defined, readily adapts itself to frame variations. The head is characterized also by its economy in production and ease of application and removal with respect to an associated frame or holder. Due to the flat and taut state of the head when applied to a frame, the same will enable such mop devices to perform their intended function more effectively or efficiently over a longer period of time than prior devices of which I am aware.

The manner shown in loop stitching the marginal edges 8b of the sheet around its outer margins for producing the continuous pocket for the drawstring not only enables the cloth to be adapted to mop frames of different sizes and shapes and formed of different materials, but, in addition, prevents undue bunching or tucking of the marginal edges of the cloth such as would occur where the marginal edge itself is hemmed to provide a channel pocket.

The loop stitching, as shown, comprises a length of

thread which, between its positions of penetration through the fabric comprising the marginal edge portions 8b of the cover sheet, has the upper portions thereof extended to provide the relatively elongated, freely flexible, drawstring-receiving loops 16. These loops are of uniform length and when the drawstring 11 is trained therethrough and drawn taut to hold the sheet 8a in place on the frame 1, the stresses applied to the stitching and the sheet are substantially uniformly distributed around the sheet margins, thereby avoiding localized bunching or tucking of the sheet; as is so often encountered in prior constructions wherein the drawstring is passed through an elongated confining hem.

I claim:

A mop head for detachable connection with the frame of a mop, comprising: a fabric sheet having a marginal edge; yarn strands attached to said sheet in spaced relation to said marginal edge; loop stitching applied around said edge and forming an internal freely flexible pocket between the sheet edge and stitching; a drawstring positioned in said pocket, said string having free manipulating ends extending laterally from said pocket and through said stitching, tightening of said strings by the drawing together of the free ends thereof in placing the string under tension serving to apply uniform tightening forces on the sheet of said fabric to draw and maintain the latter around the frame of a mop to which said head is connected; and flexible, fabric, reinforcing strain-bearing tapes secured to said sheet and overlapping said stitching adjacent the points thereon where the free end portions of said drawstring extend laterally through said stitching to absorb strains which would normally be imparted to said stitching when the ends of said drawstring are pulled relatively and laterally together.
